(57) **CLAIM**

The ornamental design for a combination electrical junction box and cover, as shown and described.

DESCRIPTION

FIG. 1 is a front perspective view of a combination electrical junction box and cover;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a front perspective view thereof, shown in a first alternate position;

FIG. 10 is a rear perspective view thereof, shown in the first alternate position;

FIG. 11 is a front perspective view thereof, shown in a second alternate position;

FIG. 12 is a rear perspective view thereof, shown in the second alternate position;

FIG. 13 is a front perspective view thereof, shown in a third alternate position;

FIG. 14 is a rear perspective view thereof, shown in the third alternate position;

FIG. 15 is a front perspective view thereof, shown in a fourth alternate position;

FIG. 16 is a rear perspective view thereof, shown in the fourth alternate position;

FIG. 17 is a front perspective view thereof, shown in a fifth alternate position; and,

FIG. 18 is a rear perspective view thereof, shown in the fifth alternate position.

Structures shown in dash-dot broken lines form no part of the claimed design.
